[57] CLAIM

The ornamental design for a conical triple end cap for use with a cable splice case, substantially as shown and described.

DESCRIPTION

FIG. 1 is a top plan view of the conical triple end cap for use with a cable splice case showing our new design. FIG. 2 is a front elevational view of said conical triple end cap;

FIG. 3 is a right side elevational view of said conical triple end cap;

FIG. 4 is a rear elevational view of said conical triple end cap;

FIG. 5 is a left side elevational view of said conical triple end cap; and

FIG. 6 is a bottom plan view of said conical triple end cap.

FIG. 1***FIG. 2******FIG. 3***

FIG. 4***FIG. 5******FIG. 6***
